UNITED STATES PATENT OFFICE.

SAMUEL H. CAMP, OF JACKSON, MICHIGAN.

CORSET.

Application filed April 11, 1919. Serial No. 289,267.

To all whom it may concern:

Be it known that I, SAMUEL H. CAMP, a citizen of the United States of America, residing at Jackson, in the county of Jackson and State of Michigan, have invented certain new and useful Improvements in Corsets, of which the following is a specification, reference being had therein to the accompanying drawings.

10 This invention relates to corsets and has particular reference to quick adjustable corset lacings.

It is the object of the invention to provide a corset having a lacing which in a 15 moment's time may be adjusted in its entirety by the wearer to establish the desired tension.

A further object is to provide for the arrangement of such a lacing at the back of 20 the corset and to adapt the same to be adjusted to any desired tension by the wearer with a minimum muscular effort, there being provided two tensioning means, one operable by each hand of the wearer which 25 on being simultaneously adjusted equalize the rotative stresses set up in the garment and eliminate any tendency to shift the same out of its proper position upon the body.

30 In the accompanying drawings:

Figure 1 is a view of the corset opened out;

Figure 2 is an enlarged view of the lacing;

35 Figure 3 is a detail sectional view taken on line 3—3 of Figure 2;

Figure 4 is a detail vertical sectional view taken on line 4—4 of Figure 2.

In these views, the reference characters 40 A and B respectively designate the parts of a two-piece corset, said parts having adjacent edges connected by upper and lower lacings E and F, the lacing E being intended to retain a permanent adjustment to the form of the wearer while the lacing

45 F may be adjusted, if desired, each time that the garment is worn. Also while the garment is in use, the wearer of the same may at times secure increased comfort

50 by a change in the adjustment of the lacing F. The remote edges of the parts A and B respectively carry the fasteners C and D, which engage each other to hold said edges into close proximity when the garment is in use. The lacings E and F are at the back of the garment while the

fastenings C and D are at the front thereof where the wearer may have ready access to the same. The adjacent edges of the members A and B are provided respectively with 60 rows of eyelets E', through which the lacing E is passed, and the lacing F passes through eyelets G in alignment with the eyelets E'. The lacing F comprises portions F' directly extending between the eyelets G of the members A and B, and portions F² and F³ respectively extending from the members A and B to a pair of tabs H and passing freely through eyelets J with which each tab is provided adjacent 65 one edge thereof. To the opposite edges of said tabs there are respectively secured buckle-slides K, respectively engaged by belt straps L. Said straps are respectively stitched or otherwise permanently secured 70 to the members A and B at points L', sail points being approximately midway between the front and rear edges of said members A and B so that they are positioned adjacent the hips of the wearer when the 75 garment is in use. Between the points L' and the front edges of the members A and B, reinforcements M are stitched to said members, preventing stresses acting in the straps L from unduly stretching such portions of the members A and B as are required to transmit said stresses. After engaging the corresponding buckle slide K, each belt strap L is return bent upon itself and passed through a keeper L². L³ indicates the loose forwardly projecting end 80 portions of the respective straps L which may be grasped, one in each hand of the wearer of the garment, in effecting an adjustment of the lacing F. The buckle 85 slides K are of a well known type permitting the straps L to slide freely when a pull is exerted upon the end portions L² to tighten the lacing F but resisting such a reverse movement of said straps as would 90 allow the lacing to loosen. By exerting a slight pressure manually upon said buckles so as to swing them to an angular relation to the tensioned portions of the straps L, the clamping effect of the buckles is overcome 95 so that the lacing F may be loosened. The tabs H preferably have facing strips N secured to their outer faces and concealing the eyelets J, said strips being free from the tabs at the edges thereof over which the 100 lacing F is passed. The use of said strips result in a more pleasing appearance and

furthermore prevents any projection upon the outer garments of the person wearing the corset from catching in the eyelets J.

Summarizing the essential features of the invention, it is to be noted, first, by exerting an opposite pull upon the end L^2 of the straps L, the lacing F may be at once tightened to any desired degree, the adjustment being automatically maintained by the slide 10 buckles K. It is further to be noted that such an adjustment may be readily accomplished by the person wearing the garment despite the fact that the lacing F is positioned at the back of the garment. The 15 wearer of the garment is not inconvenienced by necessity of attaching the adjusting straps to the garment in order to maintain the adjustment. The muscular effort required to accomplish any adjustment is decreased by having one end of the adjusting 20 strap fixed so as to afford a mechanical advantage. The use of a single lace member F facilitates both the manufacture and repairs of the garment and the fact that said lace member passes freely through the eyelets in the tabs H as well as through the eyelets in the members B and D permit all portions of the lacing to adjust themselves so as to properly transmit the stresses during 25 an adjustment.

What I claim as my invention:

1. The combination with two corset sections, of a lacing connecting adjacent edges of said sections, a pair of tab members movable over said sections near the adjacent edges thereof and freely movably engaged by said lacing, buckles respectively carried by said tab members, and a pair of straps for adjusting said lacing having ends permanently 35 secured to the respective sections and having portions respectively engaging said buckles.

2. The combination with two corset sections, of a lacing connecting adjacent edges of said sections, a pair of tab members movable over said sections near the adjacent edges thereof and freely movably engaged with said lacing for adjusting the same, adjusting straps respectively permanently secured 40

to said sections, and slide buckles respectively carried by said tab members and engaged by said straps automatically holding the latter when the same are adjusted. 50

3. The combination with two corset sections, of a lacing connecting adjacent edges of said sections, a tab member movable over each section and freely movably engaging said lacing for effecting adjustment thereof, a buckle carried by each tab member, adjusting straps secured to said sections at a point 55 remote from the edge engaged by the lacing, said straps being engageable with said buckles, and a reinforcement extending upon said sections from the point of engagement of said belt therewith to the front edge 60 thereof.

4. The combination with two corset sections provided with eyelets on their adjacent edges, of a lacing connecting said sections and passing through the eyelets thereof, 70 loops in said lacing drawn from eyelets of the same section and extending towards the opposite section, tab members provided with eyelets through which said loops freely adjustably pass, reinforcements secured to the 75 corset sections, straps secured to said reinforcements and passing rearward therefrom, and buckles on said tabs with which said straps are engaged, whereby the forward pulling of said straps will simultaneously 80 tension all of said lacings.

5. The combination with two corset sections provided with eyelets on their adjacent edges, of a lacing connecting said sections and passing through the eyelets thereof, 85 loops in said lacing drawn from eyelets of the same section and extending towards the opposite section, tab members provided with eyelets through which said loops freely adjustably pass, reinforcements secured to said 90 corset sections, buckles on said tab members, and straps secured to said reinforcements and passing rearward therefrom, said straps being return bent upon themselves and extending forwardly through said buckles. 95

In testimony whereof I affix my signature.
SAMUEL H. CAMP.
